UNITED STATES PATENT OFFICE.

WILLIAM HENRY PHILLIPS, OF BRIDGETON, NEW JERSEY.

CONVERTIBLE CHAIR AND COT.

SPECIFICATION forming part of Letters Patent No. 352,067, dated November 2, 1886.

Application filed April 15, 1886. Serial No. 198,955. (No model.)

To all whom it may concern:

Be it known that I, WILLIAM HENRY PHILLIPS, a citizen of the United States, residing at Bridgeton, in the county of Cumberland and State of New Jersey, have invented a new and useful Improvement in Convertible Chairs and Cots, of which the following is a specification, reference being had to the accompanying drawings.

10 My invention relates to improvements in convertible chairs and cots; and it consists of the peculiar and novel construction, combination, and adaptation of parts, substantially as hereinafter fully set forth, and specifically pointed out in the claims.

15 The object of my invention is to provide an improved device or article of the class named, which can be easily and rapidly converted from a reclining-chair to a cot, and vice versa, 20 without requiring the attachment or detachment of any parts, and thus render the device complete in itself; to provide an improved foot rest or support for the chair, which can be adjusted at any desired angle or position 25 with relation thereto; to provide improved means for rocking or oscillating the chair by hand or foot of the occupant, and to provide means which shall be simple, strong, and durable in construction, thoroughly effective in 30 operation, and cheap and inexpensive of manufacture.

35 In the accompanying drawings, Figure 1 is a perspective view of my invention in its adjusted position as a chair. Fig. 2 is a similar view of the device adjusted for use as a cot. Fig. 3 is a central vertical longitudinal sectional view through the device shown in Fig. 2. Fig. 4 is a detail view of the adjustable braces for the pivoted foot-rest. Fig. 5 is an 40 enlarged detail view of the supplemental supports for steadyng the rockers when the device is to be used as a cot.

45 Referring to the drawings, in which like letters of reference denote corresponding parts in all the figures, A designates the rockers, which are of the usual well-known form, and connected by a tie-rod or bar, a.

50 B designates the supporting standards, which are arranged in pairs on each rocker and carry side rails, C, at their upper ends, which are connected by cross-bars c, all of

which are suitably and rigidly connected or secured together to form the main frame.

D designates the foot-support, which comprises the side rails d, that are pivotally connected at one end, as at d', to one end of the side rails C, which latter constitute the main frame, and a cross-rail or foot-piece, d'', that is secured to the free lower ends of the side rails by means of bolts or straps d', the free ends of the side rails d being connected by a tie or cross bar, d'.

E designates the back-support that comprises the side rails e, an end rail, e', and a tie or cross bar or bars, e'', all of which are suitably secured together rigidly. The free ends of the side rails are pivotally connected, as at e', at the ends of the side rails C, opposite the ends where the foot-support is connected to said rails, and the end rail, e', of said back-support is provided at or near its middle with a bearing, f, in which an adjusting-screw, F, works to adjust the back-support in alignment with the main frame C, or at an angle thereto, as will more fully appear presently, the head 75 of the adjusting screw or bolt being provided with a shoulder, f', that prevents the screw from moving longitudinally in its bearing, and with a squared or angular head, f'', to adapt a wrench or crank, F', of any suitable construction, to be detachably fitted thereon to rotate the same.

G designates longitudinal side and brace rails which bear against the outer faces of the rails C e, and the said rails are pivoted to the 85 rails C at points g, so that they can assume the inclined position shown in Fig. 1 of the drawings, or the horizontal position shown in Figs. 2 and 3. Near one end the longitudinal brace rails or bars G are provided with a series of two or more notches or openings, g' g'', and immediately over the notches are sheaths H, which are recessed in their bottoms, as at h, and provided with a longitudinal slot, h'.

I designates brace arms or rods, which are 95 pivoted at one end on and carried by the side rails of the pivoted foot-support E, and the free ends of these brace-arms are provided with an enlargement or lug, i, and when the device is in use as a reclining-chair the foot-support is adjusted and maintained at any desired angle to the frame C by adjusting the free

ends of the pivoted brace-arms in the sheaths H and in one of the notches g' or g'' , the sheaths preventing accidental detachment or misplacement of the brace-arms, while at the same time the braces can slide freely therein. The upper or rear ends of the longitudinal brace rails or arms G are connected and braced by a cross-bar or end rail, J, against which the side rails of the adjustable back-support E bear, and by which the back is supported, and this end rail J is provided with a threaded bearing, j, in which the free end of the longitudinal adjusting-screw F works.

K designates angular brackets or supports for the pivoted brace-rails G, and these brace-rails rest on and are supported by the brackets when the device has been adjusted for use as a cot.

L designates brace-arms, which are pivoted near one end to the rockers, at or near the rear ends of the latter. These brace-arms extend beyond the lower edges of the rockers for a short distance, when they are turned to a vertical position, and the lower ends thereof rest on the floor or other place to support the cot in an approximately-horizontal position. The opposite ends of the pivoted braces are extended up to the plane of the main frame C, and they are connected by a transverse rail or bar, l, on which the back-support rests and is supported thereby. These brace-arms are turned to a vertical position when the device is adjusted for use as a cot, so that the lower ends of the said arms project beyond the lower edges of the rockers and rest on the floor, and the back-support E rests on the rail or bar l, at the upper ends thereof, said back-support being braced and strengthened by the braces when the latter are adjusted in a vertical line, and when the device is used as a rocking-chair the braces are folded so as to lie against the rockers, the free ends of the transverse bar l projecting beyond the braces and resting on the upper edges of the rockers to limit the downward movement of and retain in place the said braces L. When the braces are turned to a vertical position, they are locked in place by means of a locking-plate, M, that is pivoted at one edge on the upper face of one of the rockers, as at m, and in close proximity to one of the braces L; and at its free edge the locking-plate is provided with two arms or lugs, m', which fit on opposite sides of the brace, adjacent thereto, and as the braces are connected rigidly and for simultaneous adjustment they are both locked in place. When the braces are adjusted in a vertical line, the locking-plate is swung forward to cause the shoulders m' thereof to engage with one of the braces, and when the braces are to be folded against the rockers the locking-plate is first swung rearwardly to disengage the shoulders from the braces.

N designates a standard or rod that is arranged vertically and extends through openings in one of the side rails of the frame C and one of the rockers. This standard or rod

is arranged on one side of the frame, so that it can be conveniently grasped by hand and be depressed to oscillate the chair when it is for a rocking-chair, and in lieu of providing openings through the frame C and the rocker for the shaft or rod, the latter may be passed through proper guides on the frame and rocker, as will be very readily understood.

In order to adapt the feet of the occupant to assist in operating the chair, I provide a treadle, O, which is hinged at one end to the foot-support, as at o, and to the free end of the treadle is secured a cord, chain, or other flexible connection, O', which passes through guides p on the foot-support and main frame, and connects with the upper end of the rod or standard N. It will be observed that by depressing the rod N the rear portion of the chair will be thrown or forced downwardly, and by releasing the pressure on the said rod the weight of the chair will cause it to fall forward, and by continuing this operation the chair can be very easily oscillated back and forth. The pivoted treadle can also be depressed at its free end by the feet of the occupant to assist in rocking the chair.

The operation of my invention is as follows: When the device is adjusted for use as a reclining-chair, the back-support E is adjusted at an angle to the frame C, which latter forms the seat or bottom of the chair. The longitudinal brace-rails serve to hold the back-support in its proper position with relation to the frame C, and the said rails also form the arms of the chair, and the foot-support D can be adjusted at any angle to the frame C by means of the brace-arms I. The chair can be rocked or oscillated by the rod or standard N and the foot-treadle, or it can be held immovably in place by the foldable brace L. By rotating the screw F the relative angle of the back-support to the seat-frame C can be varied to suit the occupant and increase his comfort. When the reclining-chair is to be converted into a cot, the brace-arms L are first adjusted to bear on the floor and hold the device in place, and the crank or handle F² is applied to the head of the adjusting-screw, which is then rotated to cause the upper end of the rails G to be forced downwardly and turn on their pivots to elevate the lower ends thereof, the pivoted back-support E moving with the rails G in their adjustment, owing to the screw F connecting the end rails of the rails G and back-support. The rotation of the adjusting-screw is continued until the frames C and D lie in the same horizontal plane, or approximately so, and the longitudinal rails G rest on the angular brackets J² and outside of the rails C e, the cross-rail j supporting the free end of the pivoted back-support. The brace-arms I of the pivoted foot-support D are adjusted or thrown out of use, and the support is folded down within the plane of the side rails C. The free ends of the brace-rails G bear against the pivoted ends of the brace-arms I, and thus support the adjustable foot-support in place.

It will thus be seen that the frame C and the foot and back supports D E are all adjusted to the same plane and held in place by the brace-arms, and as the frames are all upholstered and finished a person can recline at ease on the cot thus provided.

In order to convert the cot into a chair, it is only necessary to turn the adjusting-bolt, so that the end rail *j* of the pivoted rails G will be drawn toward the end rail *e*, thereby elevating the rear end of the rails and back-support, after which the foot-support can be adjusted at the desired angle, as will be very readily understood.

I do not desire to confine myself to the exact details of construction and form and proportion of parts herein shown as an embodiment of my invention, as I am aware that changes therein can be made.

Having thus fully described my invention, what I claim as new, and desire to secure by Letters Patent, is—

1. In a convertible chair and cot, the combination of a seat-frame, a foot-support pivoted to one end thereof, the back-support pivoted to the opposite end of said frame, the brace-rails pivoted to the sides of the seat-frame at an intermediate point of their length, an adjusting-screw connecting one end of the brace-rails and the back-support, and the brace-arms intermediate of the opposite ends of the brace-rails and the foot-support, whereby when the screw is rotated the brace-rails will be turned on their pivots to move the foot and back supports in opposite directions, substantially as described, for the purpose set forth.

2. In a convertible chair and cot, a seat-frame and an adjustable back-support pivoted to the one end of the seat-frame, in combination with an adjustable foot-support pivoted to the opposite end of the seat-frame, the brace-rails pivoted to the seat-frame, the foot-support being adjustable independently of the brace-rails by hand, and the brace-arms carried by the foot-support and bearing against the brace-rails to hold the foot-support in its adjusted position, substantially as described, for the purpose set forth.

3. In a convertible chair and cot, the combination of the frame, the pivoted foot and back supports, the pivoted longitudinal rails having an end rail, and an adjusting-screw connected to the end rails of the longitudinal rails and back-support, substantially as described.

4. In a convertible chair and cot, the combination of a frame, a pivoted foot-support, a pivoted back-support, the longitudinal rails pivoted to the frame and having an end rail

on which is fitted and supported the side rails 60 of the back-support, and an adjusting-screw working in bearings of the end rail and the pivoted back-support, for adjustably connecting said parts, substantially as described.

5. In a convertible chair and cot, the combination of the seat-frame, a foot-support pivoted to one end of the seat-frame and normally depending therefrom, a back-support pivoted to the opposite end of the seat-frame, the longitudinal rails pivoted to the seat-frame at an intermediate point of their length, and connected at their rear ends to the back-support and having the racks at their front ends, and the swinging braces carried by the foot-support and engaging the racks at their free ends 75 to retain the foot-support at any desired angle to the seat-frame, substantially as described, for the purpose set forth.

6. In a convertible chair and cot, the combination of a seat-frame, a foot-support pivoted thereto at one end, a back-support pivoted to the opposite end of the seat-frame, the longitudinal side rails pivoted at an intermediate point of their length to the seat-frame and connected at their rear ends with the back-support and having the racks at their front ends, the slotted sheaths affixed to the front ends of the longitudinal rails and concealing the racks thereon, and the swinging brace-arms pivoted to the foot-support and having 85 the enlarged free ends fitted in the slotted sheaths and engaging the racks of the longitudinal side rails, substantially as described, for the purpose set forth.

7. The combination of a frame having the 95 rockers, a foot and back support, the longitudinal rails, a rod, N, guided on the frame, and a movable foot-piece or treadle supported on the foot-support and having a connection with the rod, substantially as described, for 100 the purpose set forth.

8. In a convertible chair and cot, a seat-frame provided with the rockers and the adjustable seat and back supports, in combination with the folding braces L, pivoted to the 105 rockers, and projecting beneath the same when adjusted to an upright position, and a swinging locking-plate carried by one of the rockers to lock the braces against movement, substantially as described, for the purpose set 110 forth.

In testimony that I claim the foregoing as my own I have hereto affixed my signature in presence of two witnesses.

WILLIAM HENRY PHILLIPS.
